J. Maginnis.

Tailoring.

No 8566.

Patented Dec. 2. 1851

UNITED STATES PATENT OFFICE.

JAS. MAGINNIS, OF LOCKPORT, NEW YORK.

TAILOR'S MEASURE.

Specification of Letters Patent No. 8,566, dated December 2, 1851.

To all whom it may concern:

Be it known that I, JAMES MAGINNIS, of Lockport, in the county of Niagara and State of New York, have invented a new and Improved Instrument for Measuring Men and Drafting Coats; and I do hereby declare that the following is a full, clear, and exact description of the construction and operation of the same, reference being 10 had to the accompanying drawings, making a part of this specification, in which—

Figure 1 is a view of the instrument as set to the form of the body of a coat, the dotted lines are the body of the coat. Fig. 15 2 shows the instrument as set to the back when the measure is taken, and Fig. 3, its application to the breast and shoulder.

(R) is a strap that extends from the socket bone of the neck to the waist parallel with 20 the back seam.

(E) is a strap that extends from the center of the back to the breast.

(B) is a strap that clasps into strap E at 25 the back and is carried around and hooked on to it in front, as represented in the drawings.

(G) is a strap that extends from the center of the back of the waist to the front.

(N) is a strap that clasps into strap (G), 30 at the hollow of the waist, and is carried around and hooked in front. Straps, N, and B, serve to hold the instrument on the body.

(C) is a square that slides on straps, R, 35 and E from the center of the back to the armhole.

(A and S,) is a gage with two arms connected by a cross bar marked (L), in the drawings, two straps are attached to the 40 top of the inner arm (these straps serve to measure the length of the shoulder) and the outer arm passes up and forms a semicircle over and around the top of the inner arm, this semicircle is slit through the center and 45 forms a way for the shoulder straps to turn on, this gage slides on strap (E) from the front backward, it locates the front of the armhole and gives the diameter of the same 50 the pitch of the shoulder and width of breast.

(L) is a strap that is attached to the cross bar of the gage it turns on a pivot and serves to measure the width of the breast also the height of the same.

(O) is a strap that extends from the pivot 55 (A) on top of the inner arm of the gage,

to the socket bone of the neck. This strap measures the length of the upper front of the shoulder and gives the forward or backward pitch of the same.

60

(P), is a strap that measures the length of the lower point of the shoulder.

(K) is a strap that measures the length of the breast, from strap (I), "the distance that a coat is carried in at the waist is de- 65 termined."

The nature of my invention consists in its capability of contraction or expansion so as to give a complete graduation of sizes from the smallest boy to the largest man. 70 It can be set to any sized coat without taking the measure hence its great utility in cutting ready made clothing. Again my instrument is so arranged that, when it is properly adjusted or set to the body, as 75 illustrated by Figs. 2 and 3 in the drawings, by unhooking it in front it springs out straight becomes a pattern and conveys the shape, as well as the size, of the individual to the cloth, (see Fig. 1 in drawings). Further my instrument works on the back by 80 sliding from the center toward the armhole and on the breast from the front backward toward the armhole so that it gages the shoulder and gives the exact size and lo- 85 cality of the armhole.

To enable others skilled in the art to make and use my invention I will proceed to describe its construction and operation. The instrument is made of brass or any other 90 suitable metal, rolled down quite thin, it is then cut into the form of the various parts composing the instrument, designated by the letters R, E, B, G, N, C, A, S, L, O, D, P, K, I; the straps composing the instrument are slit through the center the same as illustrated in the drawings, and numbered in inches and quarters the same as a common rule. The straps cross each other at right angles and screws with flat heads 95 are put through these slits the heads of the screws on the underside and nuts on the top so that, when the instrument is set by turning these screws it is made fast and retains its form until applied to the cloth.

100

105

What I claim as my invention and desire to secure by Letters Patent is—

The gage designated by the letters, A and S, in the drawings. This gage has two arms slit through the center from the cross 110 bar down, as illustrated by Fig. 1, in the drawings, the front arm extends up and

forms a semicircle over and around the top of the inner arm, this semicircle is slit through the center and forms a way for the two shoulder straps which are attached by a pivot to the top of the inner arm to turn on, with screws to set them to the desired place, the semicircle is designated by the letter D, in the drawings; this gage moves horizontally on strap, E, from the front backward or vice versa until it strikes

same, and is set by screws to the desired place, again this gage can be drawn perpendicularly so as to increase the length of the shoulder, for a very full breasted man 15 or contracted so as to fit a hollow breasted man.
